UNITED STATES PATENT OFFICE

AUDLEY E. HARNISBERGER, OF CHICAGO, ILLINOIS, ASSIGNOR TO THE PURE OIL COMPANY, OF CHICAGO, ILLINOIS, A CORPORATION OF OHIO

MEANS FOR PRODUCING HEAT-TRANSFER CONDUITS

Application filed September 20, 1927. Serial No. 220,770.

This invention relates to an improved means for producing heat transfer conduits and has for its outstanding object the provision of a simple yet efficient means for producing heat transfer conduits by positioning a plurality of longitudinally spaced, transversely disposed collars on a length of straight tubular stock and in then subjecting the latter to intense radially directed pressures, by means of which the metal between the collars will be displaced and crowded into engagement with the collars so as to firmly retain the latter in the desired spaced positions upon the conduit.

For a further understanding of the invention reference is to be had to the following description and the accompanying drawing, wherein:

Figure 1 is a vertical longitudinal sectional view taken through a heat transfer conduit formed in accordance with the present invention and illustrating the apparatus employed in carrying out the invention,

Figure 2 is a vertical transverse sectional view on the line 2—2 of Figure 1,

Figure 3 is a side elevation of the displacing head.

Referring more particularly to the drawings the numeral 1 designates generally the improved extended surface tube or conduit formed in accordance with the present invention. This conduit has application in various heat exchange equipment involving transfer of heat from a gas, vapor or liquid on the outside of the tube to a gas, vapor or liquid in the interior of the tube. The tube may be formed from any suitable metal such as steel, brass or any suitable alloy, depending upon the service for which the tube is to be employed. Arranged on the tube at longitudinally spaced intervals are rings or collars 2, which are of suitable dimensions and arranged in predetermined spaced relationship, the internal diameter of said collars being just sufficient to allow the same to be

slipped on the outer surfaces of the tube body 3. The body is then mounted on a lathe bed or other similar machine with the lead screw 4 of such machine disposed axially within the tube body. The tube is then clamped rigidly, and the lead screw 4 is suitably connected to the lathe chuck or face plate (not shown).

An expander 5 is then drawn through the tube by the rotation of the screw 4. This expander, in a simple form of the invention, consists of a head 6, provided with a plurality of radially extending arms 7, to which are pivoted as at 8 a plurality of longitudinally extending swinging frames 9. These frames are provided with recesses for the reception of axles 10 provided in connection with hardened steel rollers 11, which engage with the inner surfaces of the tube body 3. The operating position of the rollers 11 or the frames 9 are controlled by the medium of set screws 12, the latter being provided with heads 13, and the inner ends of said screws are set to bear upon the head 6 of the expander. Lock nuts 14 engage with said screws to insure the retention thereof in adjusted positions.

It will be seen that the steel rollers 11 may be said to bear against the inner wall of the tube body, displacing the metal of the latter by forcing it outwardly into the rings or collars 2, thereby forming slight undulations as indicated on the interior and exterior of the conduit, causing said tubes between said collars to possess a greater diameter than the internal diameter of the collars. By this construction and operation the rings or collars 2 are firmly united with the conduit body 3 to produce a fixed, unitary construction wherein relative movement between the rings or collars and the conduit body is effectively precluded.

The expander, having been drawn through the tube body, is shifted in position to an extent equivalent to the width of one of the

rollers 11 and then again forced or drawn through the body. This process is repeated until the desired expansion is obtained. It is obvious that in place of the adjusting screws 12 a wedge shaped collar could be forced 5 underneath the swinging frames 9, thereby securing uniform adjustment of all the rollers.

Other modifications of the specific type of 10 expander disclosed may be utilized without departing from the spirit of the invention. For example, the expander has been shown as provided with four rollers. This number may be doubled if desired or two or more 15 expanders may be utilized at the same time with their rollers spaced equidistantly around the interior of the tube.

Of course, the interior of a conduit so 20 formed will not be smooth, but in the majority of heat transfer operations this should not prove objectionable. It is also understood that the rings or collars may be of a different material than the tube body, for 25 example, the utilizing of rings having a lower coefficient of expansion than the tube body itself, so as to prevent loosening of the rings under extremely high temperature conditions.

What is claimed is:

1. An expanding tool comprising a longitudinally extending screw arranged to be positioned axially within a tube, a head formed to include a hub internally threaded to receive the screw, a plurality of radially swinging arms pivotally mounted at one end upon 35 said head and lying in planes substantially parallel with said screw, rollers mounted for rotation on said arms and rotatable about axes arranged transversely to the axis of the screw, and means carried by the outer ends of said 40 arms and engageable with said hub for controlling the radial adjustment of the arms and the rollers carried thereby, whereby said rollers may be crowded into contact with the inner peripheral walls of the tube in which 45 the same is positioned.

2. An expanding tool comprising a head, means for moving said head longitudinally through a tube, a plurality of relatively swinging arms having certain of their ends 50 pivotally connected with said head, said arms being disposed generally in planes substantially parallel to the longitudinal axis of a co-operating tube, rollers carried by the intermediate portions of said arms and turnable 55 about axes disposed transversely of the arms, and adjusting devices carried by the outer or free ends of said arms and co-operative with said head for controlling the radial swinging movement of said arms and the 60 rollers carried thereby with respect to said head.

3. An expanding tool comprising a longitudinally extending screw, a head having a hub internally threaded to receive the screw 65 and rotatable about the axis of the screw, a

plurality of arms having certain of their ends pivotally connected with said head and extending substantially parallel with said screw, rollers mounted upon the intermediate portions of said arms, and threaded adjusting devices carried by the outer or free ends of said arms and engageable with said hub to control the radial swinging movement of said arms with respect to said head. 70

In testimony whereof I affix my signature. 75
